DISPENSING CLOSURE FOR CONTAINERS

Substitution for abandoned application Serial No. 65,543, filed December 7, 1915. This application filed February 12, 1930. Serial No. 427,998.

This invention relates to dispensing closures for containers such as collapsible tooth paste tubes and the like, the present application being a substitution for my abandoned 5 application filed December 7, 1915, Serial No. 65,543.

Ordinarily, such tubes are provided with closures which are removable and which are consequently liable to be lost or misplaced, or 10 where such closures are so constructed as to be capable of manipulation to permit the discharge of the contents of the tube and yet remain permanently connected with the discharge spout, they usually require manipulation by one hand while the tube is held in 15 the other hand, which is inconvenient.

The invention has for its primary object, therefore, to provide a closure which will effectually prevent the evaporation or caking 20 of the contents of the tube and which may yet be readily manipulated by the thumb of the hand in which the tube is grasped to permit the discharge of the contents of the tube or to close the outlet opening from the spout 25 of the tube.

Another object of the invention is to provide a device of this character having means to cut off the supply of paste so that the tube may be laid upon any convenient supporting 30 surface without likelihood of the contents being contaminated.

A further object of the invention is to provide a novel means for locking the closure in closed position, which means, however, 35 will not interfere with the intentional swinging of the closure to open position.

Still further objects of the invention not specifically mentioned in the following will appear during the course of the following 40 description.

In the drawings:

Figure 1 is a perspective view illustrating the manner in which the device is to be employed.

45 Figure 2 is a vertical longitudinal sectional view through the discharge end of the tube.

Figure 3 is a horizontal sectional view on the line 3-3 of Figure 2, looking in the direction indicated by the arrows.

Figure 4 is a side elevation of the discharge end of the tube, the closure thereof being illustrated in open position.

Referring now to the drawings, the numeral 1 indicates in general a collapsible tube such as is usually employed for carrying tooth paste, glue, and the like. Formed on the end of said tube is a discharge spout 2. This spout 2 is integral or connected with the discharge end of the tube 1 and comprises a 55 solid substantially frusto-pyramidal body of suitable dimensions having relatively inclined rear and forward sides 3 and 4 respectively, and relatively inclined lateral faces 5, the faces 5 being inclined, not only in an upward 60 direction toward each other, but lying also in planes converging in the direction of the forward face 4 of said body. The body 2 is provided with a passage 6 which communicates with the interior of the tube 1 through 65 the under side of the body and which opens through the forward face 4 of the body, the passage being gradually restricted in the direction of its open end, as clearly illustrated in Figures 2 and 3 of the drawings. It will 70 now be apparent that when the tube 1 is pressed, the paste within the tube will be forced outwardly through the passage 6, issuing in a ribbon-like stream through the open end of said passage, as illustrated in Figure 1 75 of the drawings, and in such manner that the paste may be laid along the bristles of a tooth 80 brush.

The closure for the spout above described comprises sides 7 which are inclined and 85 which lie in converging planes so as to snugly embrace the lateral faces 5 of the body of the spout when the closure is in closed position, a top 8 which is arranged to rest upon the upper face of the body 2 of the spout, as 90 shown in Figure 2 of the drawings, and a forward wall 9 which will be more specifically described hereinafter. In order that the closure may be connected with the spout for pivotal or swinging movement, a pin 10 is 95 fitted through the spout 2 near the upper rear corner thereof and is pivotally engaged at its ends in the side walls 7 of said closure, or, if desired, the closure may be similarly connected in any other suitable manner. In or- 100

der that the closure may be conveniently swung from open to closed position, and vice versa, a lip 11 is provided at the rear edge of the top 8 of the closure and may be engaged by the thumb of the hand in which the tube is grasped, in the manner clearly shown in Figure 1 of the drawings. At the junction of the side walls 7 of the closure with the forward wall 9 thereof, said side walls are struck 10 outwardly as indicated at 12, to form channels 13 receiving the edges of a lining 14 of cork or any other suitable material, which lining covers the inner face of said wall 9, as shown in Figures 2 and 3 of the drawings. 15 and is designed to close the discharge end of the passage 6 in an air-tight manner. In order that the discharge end of the passage may be completely closed, the forward wall 9 of said closure is provided with an elongated longitudinally extending indentation 15 resulting in a correspondingly shaped rib 16 which bulges the intermediate portion of the lining 14 in the manner indicated at the numeral 17, so that, when the closure is 20 swung down to closed position, this bulged portion of the lining will seat within the discharge end of the passage.

In order that the closure may be locked in closed position, the side faces 5 of the 30 spout 2 are provided each with an indentation 18 adapted to receive a protuberance 19 formed by indenting the corresponding wall 7 of the closure, said closure being formed from resilient metal so that as it is swung 35 to closed position, the protuberance 19 will spring into the indentations 18. In order that the closing movement of the closure may not be interfered with, a groove 20, shallower than the indentations 18, is formed in each 40 side face of the spout 2 concentric to the pivot for the closure and communicating at its lower end with the respective indentation and at its upper end terminating at the top of the face of the body in which it is formed. As 45 an additional means for locking the closure in closed position, the lower edge of the front wall 9 of the closure is provided with a flange 21 designed to ride over the lower portion of the forward face 4 of the body 2 and spring 50 into engagement with a transverse seating groove 22 formed in the face 4 at the bottom thereof. The engagement of this flange 21 in the groove 22 serves also as an additional means for preventing the entrance of air or 55 moisture into the passage 6 and also prevents leakage of the paste in the event that the cork lining becomes worn.

What is claimed is:

1. A container including a body portion 60 having a substantially frusto-pyramidal spout extending longitudinally from one end thereof and provided with a discharge passage opening through one end wall of the spout, a closure corresponding in shape to the 65 spout and pivotally mounted thereon and hav-

ing an inwardly bulged portion adapted to fit within the mouth of the discharge passage when the closure is in closed position, the ends of the side walls of the closure on opposite sides of the bulged portion being bent to 70 form channels, and a packing strip seated in said channels and extending over the bulged portion of the closure.

2. A device of the class described comprising a compressible container having a solid substantially frusto-pyramidal discharge spout projecting longitudinally from one end thereof and having a laterally and downwardly inclined wall, there being a discharge 75 opening formed in the spout and having one end thereof communicating with the interior of the container near the center thereof and its other end opening through the inclined wall of the spout near the center thereof, a closure conforming to and pivotally mounted 80 on the spout and having an inclined end wall, a lining member carried by the inclined end wall of the closure and adapted to project within the mouth of the discharge passage when the closure is in closed position, a finger 85 piece carried by the pivoted end of the closure, and interengaging locking means formed on the spout and closure respectively.

3. A device of the class described comprising a compressible tube having a solid substantially frusto-pyramidal discharge spout projecting longitudinally from one end thereof and provided with a downwardly and laterally inclined end wall and side walls converging in the direction of said end wall, said 95 spout being formed with a discharge passage, the mouth of which is constricted and opens through the inclined end wall of the spout, and a closure pivotally mounted on the spout and having an inclined end wall coacting with the 100 inclined end wall of the spout, the inner face of the inclined end wall of the closure being adapted to project within the constricted mouth of the discharge passage when the closure is in closed position.

In testimony whereof I affix my signature.
